UNITED STATES PATENT OFFICE.

VITTORIO BUFFULINI AND RICCARDO ROTTENBACHER, OF TRIESTE, AUSTRIA-HUNGARY.

WRECK-RAISING APPLIANCE.

1,030,869.

Specification of Letters Patent.

Patented July 2, 1912.

Application filed November 6, 1911. Serial No. 658,687.

To all whom it may concern:

Be it known that we, VITTORIO BUFFULINI and RICCARDO ROTTENBACHER, subjects of the Emperor of Austria-Hungary, and residents of Trieste, Austria-Hungary, have invented certain Improvements in Wreck-Raising Appliances, of which the following is a specification.

Our invention relates to a device for indicating the position and facilitating the raising of sunken ships, and consists in the provision of a buoy which is so connected to the vessel as to allow of being set free to float on the water surface if the vessel should happen to sink or, in the case of submarine vessels, get out of control. Hoisting cables for raising the vessel are permanently connected thereto which cables are in their turn connected by minor cables to the buoy, the latter being thereby held on the water surface so as to indicate that the vessel is sunk and in need of assistance. To raise the vessel it is only necessary to haul in the cables and connect the hoisting cables to the cranes of the salvage vessels, for which operation no divers need be employed. Electric communication, which is automatically put into operation, is established between the vessel and the buoy for the purpose of illuminating the latter at night. Telephonic communication is also provided.

In the accompanying drawings the invention is illustrated by way of example in connection with a submarine vessel, the figure representing a sectional view of the complete arrangement.

On the deck 1 of the vessel a hollow cylindrical buoy 3 is supported by means of feet 2. A screw-spindle 4 is fitted in the deck 1 so as to engage a socket in the bottom of the buoy and thus hold the latter connected to the vessel. The buoy, which has a bevelled upper edge, is surmounted by a lamp 6 casing 5 fitted with light refracting lenses 6 and is divided by two horizontal partitions 7 into three superposed compartments. In the lower compartment four horizontal cable drums 9 are radially arranged about a centrally disposed tube 8, said drums being

wound with thin steel cables 10 the ends of which are passed in a water-tight manner through the bottom of the buoy and connected to the free ends of strong cables which are lodged in cages 11 and fastened to eyed brackets 12 on the deck 1.

The central compartment of the buoy has two vertical supports 12' which carry another horizontal cable drum 13. This drum is made of electrically insulating material such as stabilit or the like and is fitted at each end with two mutually insulating flanges of conducting material. A cable 14, composed of four electrically conducting strands is wound on the drum 14 and passed through the bottom of the buoy and through the deck 1, in a water-tight manner, into the interior of the vessel. The inner end of this cable is untwisted, and the separate strands are connected to the four conducting flanges of the drum, one to each. The single strands are preferably insulated by a rubber coating and the four strands together wrapped up in several layers of linen which has been saturated with paraffin, tar, pitch, or the like. Access to the upper compartment of the buoy can be had through a normally covered manhole 15. In this compartment a telephone apparatus 16 is arranged which is connected by means of a pair of sliding contacts 18 to one pair of the conducting flanges of the drum 13. An electric lamp 17, preferably fitted with salted carbons, is arranged in the casing 5 and connected by means of another pair of sliding contacts 18' to the opposite pair of conducting flanges of the drum 13.

In the interior of the vessel an electric accumulator 25 is provided which is connected by means of leads 24 to a double pole switch 23 and to a time switch 26, these elements being also connected to those strands of the cable 14 which lead to the lamp 17. The circuit is normally interrupted by the switch 23 whose switch lever is connected by means of a traction element 22 to a double-armed lever 21. A vertical rod 20 is pivotally attached to one arm of the lever 21 and has its upper end projecting through and guided in the deck 1. A

spring 19, encircling the rod tends to press the same upward so as to turn the lever 21 and the switch lever for closing the circuit. Such closing of the circuit is normally prevented by the buoy against the bottom of which the rod 20 abuts. The time switch 26, which may have the construction disclosed in the German Patent No. 218782 of May 22, 1909, is adapted to maintain the circuit closed by night and interrupted in the day-time. A telephone apparatus 27 in the vessel is connected by leads 29 to a battery 28 and to those strands of the cable 14 which lead to the telephone apparatus 16. To tighten the cables 10 and 14 to the bottom of the buoy, cork rings may be employed which are secured to the buoy so as to embrace the cables.

The modus operandi is as follows:—If, the vessel being submerged, it should be found impossible for one reason or another to take her to the water surface by her own power, then the screw 4 is turned so as to set the buoy free. Being lighter than its volume of water, the buoy at once rises to the water surface, thereby unwinding the cables 10 and 14 from the drums and pulling them through its bottom. At the separation of the buoy from the vessel the rod 20 is released so that, influenced by the spring 19, it can operate the switch 23 for doing its part of the closing of the lamp circuit. The circuit is now controlled by the time switch 26 which switches the lamp on in the evening and off in the morning. The buoy, which is thus visible night and day, indicates the position of the vessel and her need for assistance. The salvors, called to the place after the discovery of the buoy, have merely to haul in the ends of the hoisting cables by means of the cables 10 and connect them to the cranes of the pontoons whereupon the submerged vessel can be raised to the surface without the assistance of divers. Telephonic communication is meanwhile kept between the salvors and the crew of the vessel through the medium of the instruments 16 and 27 and the cable 14. The lamp 17 may under normal conditions be employed for signaling purposes.

When the apparatus is employed in connection with an ordinary vessel the screw spindle 4 can be discarded, the buoy being then mounted in a casing which it is capable of leaving spontaneously in case the vessel should happen to sink. It is also possible to discard the drums 9 and simply roll the cables 10 up together with the hoisting cables in the cages 11. For ships running on shallow water the hoisting cables may be dispensed with and the raising of the vessel effected by means of pulley blocks. In that case the cables 10 are connected directly to the brackets 12, and the lower pulley of

each block is fitted with a guide element by means of which it can be guided along the cable 10 through the water, a hook being secured to the pulley in such a manner as to snap automatically into connection with the bracket 12 when it reaches the latter.

We claim:

1. A device for indicating the position and facilitating the raising of sunken ships, comprising a buoy mounted on the deck of the vessel so as to allow of being set free to float on the water surface if the vessel should sink, hoisting cables for raising the vessel connected to and carried by the latter, minor cables connecting the outer ends of the hoisting cables with the buoy so as to control the position of the latter when afloat and enable the ends of the hoisting cables to be brought to the surface, an electric lamp in the buoy for illuminating the latter at night, electric connections between the vessel and the buoy for supplying power to said lamp, means for maintaining the electric circuit normally interrupted, and means for closing said circuit automatically when the buoy leaves the vessel, substantially as set forth.

2. A device for indicating the position and facilitating the raising of sunken ships, comprising a buoy mounted on the deck of the vessel so as to allow of being set free to float on the water surface if the vessel should happen to sink, hoisting cables for raising the vessel connected to and carried by the latter, minor cables connecting the hoisting cables with the buoy for controlling the position of the latter when afloat and enable the ends of the hoisting cables to be brought to the surface, a casing fitted with light refracting lenses surmounting the buoy, an electric lamp in said casing, an electric source in the vessel, electric connections between said lamp and said electric source, a switch keeping the circuit normally interrupted, and means for automatically actuating said switch so as to close the circuit when the buoy leaves the vessel, substantially as set forth.

3. A device for indicating the position and facilitating the raising of sunken ships, comprising a buoy mounted on the deck of the vessel so as to allow of being set free to float on the water surface if the vessel should happen to sink, hoisting cables for raising the vessel connected to and carried by the latter, minor cables carried by drums in the buoy and connected to the hoisting cables so as to control the position of the buoy when afloat and enable the ends of the hoisting cables to be brought to the surface, an electric lamp on the buoy for indicating the position at night, an electric source in the vessel, a cable supplying power from said source to said lamp, an electric switch

arranged in the vessel and adapted to hold the electric circuit normally interrupted, a spring-actuated rod arranged in the vessel so as to be depressed by the buoy in opposition to its spring when the buoy rests on the vessel, and connections between said rod and said switch causing the latter to be operated for closing the circuit as soon as the

rod is released by the buoy, substantially as set forth.
